MOPPING APPARATUS

Edward A. Twerdahl, Evanston, Ill.

Application September 20, 1946, Serial No. 698,275

3 Claims. (Cl. 15—260)

1

The present invention relates to apparatus for mopping floors and the like and more particularly to an improved mop pail structure and mop construction which may be used in combination to reduce the drudgery ordinarily attendant with this type of work.

Conventional mopping apparatus consists of a string mop and a water pail for containing the mopping liquid, with no facilities being provided for wringing out the mop. This means that in using the apparatus the mop must be wrung out by hand. Various crank operated wringing devices usually adapted for attachment to the mop pail, have been developed and sold commercially to eliminate the hand wringing operation. However, all such devices as well as hand wringing require that the mop user stoop over and either crank the wringing device or twist or squeeze the mop during each mop wringing operation. Hence, conventional methods of mop wringing are laborious and time consuming. Further, due to the round construction and small bottom surfaces of most mop pails, there is considerable likelihood of overturning the pail during mop wringing, particularly when a wringing device of the character referred to is attached to the pail. Moreover, in the use of conventional mopping apparatus, the dirty liquid picked up from the floor is ordinarily squeezed out into the liquid in the pail, with the result that the cleaning liquid quickly becomes dirty and must be frequently changed. This further increases the labor involved in mopping a given floor area.

It is an object of the present invention, therefore, to provide improved, simple and low cost mopping apparatus of light easily portable construction which completely obviates the above-described operational disadvantages.

It is another object of the invention to provide improved mopping apparatus which may be easily operated without requiring any stooping or muscular exertion on the part of the mop user during mop wring out operations and without the mop user's hands coming in contact with the cleaning liquid, thus permitting the use of strong detergents or cleaning solvents in the cleaning liquid.

It is a further object of the invention to provide improved mopping apparatus of the character described which is so arranged that the dirty liquid squeezed from the mop during the wring out operations is not intermixed with the cleaning liquid.

According to a still further object of the in-

2

vention, an improved mop pail structure is provided which requires only a small amount of storage and shipping space and yet is very difficult to tip over in use.

5 The invention both as to its organization and method of operation, together with further objects and advantages thereof, will best be understood by reference to the following specification taken in connection with the accompanying drawings, in which:

Fig. 1 is an elevational perspective view of improved mopping apparatus characterized by the features of the present invention;

15 Fig. 2 is a view similar to Fig. 1 but illustrating certain components of the apparatus in changed positions;

Fig. 3 is an elevated perspective view of the pail structure forming a part of the apparatus;

20 Fig. 4 is a side sectional view taken along the lines 4—4 in Fig. 2;

Fig. 5 is a side elevational view of the pail structure shown in Fig. 3;

25 Fig. 6 is a fragmentary sectional view taken along the lines 6—6 in Fig. 4.

Referring now to the drawings and more particularly to Figs. 1, 2 and 3 thereof, the present improved mopping apparatus is there illustrated as comprising a pail structure 10 and a mop structure indicated generally at 11. In brief, the pail structure 10 comprises an open top liquid container 12 of generally rectangular configuration having side walls 12a and 12b and end walls 12c and 12d extending upwardly and flaring outwardly from a bottom wall 12e. The purpose of this particular configuration is twofold, i. e., to permit a number of the containers to be nested for shipment and storage and to provide a large bottom area which minimizes the likelihood of the container being overturned in use.

40 If desired, the container 12 may be formed of a single piece of thin gauge metal and provided with a reinforcing bead around the open upper edge thereof. Alternatively it may be comprised of a number of sheet metal panels assembled together to form the desired configuration and seam welded along the meeting edges thereof to render the space within the panels liquidtight. Along the open top edge of the container 12, the pail structure is provided with combination carrying and mop squeezing means comprising a rectangularly shaped bail 13, the base rod 13d of which is pivotally supported upon the container 12 approximately midway between the end

45 panels 12c and 12d by means of pivot lugs 14

and 15 riveted or otherwise suitably mounted upon the container side walls 12a and 12b. The other transversely extending section 13a of the bail 13 is utilized pivotally to support a wooden grip spool 16 having a U-shaped bail threaded therethrough and provided with legs pivotally attached to the bail section 13a.

The mop squeezing means carried by the bail 13 is illustrated as comprising a heavy wire screen 17 covering the area defined by the four sections 13a, 13b, 13c and 13d of the bail and fixedly secured to all of these bail sections as by soldering, welding or the like. Regardless of the manner in which the mop squeezing structure is formed, this structure should have openings therethrough of sufficient size to permit free liquid drainage into the container 12 in the manner more fully pointed out below.

With the above-described construction of the combination carrying and mop squeezing means, the bail 13 may be raised to an upright position relative to the container 12, i. e., to the position shown in Fig. 3 of the drawings, for the purpose of carrying this container from place to place. In normal use, however, the bail occupies a lowered position in engagement with the upper edge of the container 12, such that the screen 17 covers approximately one-half of the open top area of the container and the other half of this area is left open to admit the head of the mop 11. In this regard it will be understood that the bail 13 is shaped and sized to match approximately one-half the upper edge contour of the container 12 so that the described partial coverage of the open top of the container by the screen 17 is obtained when the bail occupies its lowered position.

For the purpose of providing an open top liquid receiving well within the container 12 to receive soiled or dirty liquid squeezed from the mopping element of the mop 11, a second container indicated generally at 18 is provided. As best shown in Figs. 4 and 5 of the drawings, this second container is also of light gauge sheet metal construction, is detachable from the container 12 and is sized and shaped to fit snugly within the container 12 adjacent one end thereof. More specifically, the second container 18 is comprised of end walls 18c and 18d and a pair of side walls 18a and 18b which meet at the bottom to form a chamber or well of triangular cross section. Preferably, these four walls are so sized and shaped that when the container is inserted into position within the container 12, the wall 18b fits snugly against the outer container end wall 12d and the walls 18c and 18d fit snugly against the outer container side walls 12b and 12a, respectively.

The purpose of slanting the wall 18a of the second container downwardly and toward the end wall 12d of the outer container to form the described well of triangular cross section is to prevent the center of gravity of the pail structure as a whole from being shifted too far to the left as viewed in Fig. 4 of the drawings when the large outer container 12 is filled with cleaning liquid and the second container 18 is empty. A further important feature of the described construction resides in the fact that cleaning liquid in the main reservoir of the large container 12 presses against the wall 18a to force the wall 18b against the end wall 12d of the container 12 and thus prevent the end of the container 18 adjacent the wall 12d from being forced upward. In order to prevent the other end of the container 18 from floating upward in the liquid filled container 12,

the end walls 18c and 18d of the container 18 are respectively provided with clips 19d and 19e along the upper edges thereof which are adapted yieldingly to embrace the beaded upper edges of the outer container side walls 12b and 12a, respectively, in the manner best shown in Fig. 6 of the drawings. For the purpose of facilitating removal of the second container 18 from the main container 12, the end walls 18c and 18d are also provided with lifting flanges 19a and 19b which project laterally outward from the side walls 12b and 12a of the main container in the manner best shown in Figs. 1, 2, 3 and 6 of the drawings.

Referring now more particularly to Figs. 1 and 2 of the drawings, the present improved mop is there illustrated as comprising a combination support and squeezing plate 20 of rectangular configuration having substantially the same size and shape as the mop squeezing screen 17. This plate is adapted to be mounted upon the threaded end of a mop handle 22 by means of a threaded socket element rivet connected to the plate 20 at the upper side thereof. At its underside, the plate 20 is adapted to support a mopping element 23 which preferably is of the synthetic or natural sponge type and may be of any reasonable thickness such, for example, as two inches. In order to secure the mop element to the plate 20, this element is stitched, adhesively bonded or otherwise secured to a flexible textile fabric backing element having free end extensions, which are adapted to be wrapped around the front and rear edges of the plate 20, the backing element being laced over the plate 20 to secure the mopping element thereto. For the purpose of forcing the plate 20 toward the mop squeezing screen 17 to expunge cleaning liquid from the mopping element 23, a pair of raised steps 29 and 30 are mounted upon the plate 20 along the top side thereof. More specifically, these steps are of identical U-shape configuration and each is provided with laterally extending leg ends rivet connected to the plate 20. Preferably, the two steps are mounted to extend transversely of the long side of the plate 20 and are spaced equidistant from the respective ends thereof on opposite sides of the socket 21.

Briefly to consider the manner of using the described apparatus, it will be understood that in the usual floor cleaning operation, the second container 18 is left in place within the main container 12 to receive soiled or dirty water expunged from the mop element 23. The cleaning solution, usually water intermixed with soap or another detergent, is mixed within the main chamber of the container 12 in the usual manner. After the cleaning solution is thus mixed at a sink or the like, the bail 13 may be used to carry the pail structure 10 from place to place as the mopping operation proceeds. However, in any given location the bail structure remains in its lowered position against the upper edge of the container 12 to cover the open top of the second container 18. In order to soak the mopping element 23 with the cleaning solution, it is only necessary to insert this element through the open space in the top of the container 12 to submerge the same in the solution and then withdraw the same to carry out the desired mopping operation. Each time the mopping element 23 becomes filled with soiled or dirty solution picked up from the floor being cleaned, the mop may be hand manipulated to position the mopping element 23 on the mop

squeezing screen 17 in the manner illustrated in Fig. 2 of the drawings. With the mopping element thus positioned, the user of the mop may place one foot on the steps 29 and 30 and step down on these two steps, thereby to force the plate 20 toward the screen 17, compress the sponge, and thus expunge the soiled or dirty cleaning solution from the mopping element 23. As the liquid flows out of this element, it drains through the openings in the screen 17 into the well defined by the second container 18. In this regard, it may be pointed out that when tightly compressed, mopping elements of the synthetic or natural sponge type have the characteristic of retaining only a small fraction of the liquid which may be contained therein when fully expanded. Hence, while some contamination of the cleaning solution in the main chamber of the container 12 does occur, it is negligible as compared with that which occurs when the dirty solution picked up from the floor is squeezed back into the cleaning solution. After the well within the second container 18 becomes filled, this container may easily be detached from the main container 12 and dumped. Thus the mopping operation may be continued without frequent changes of the cleaning solution.

In certain cases it may be desired to use the mop 11 strictly as a dust mop rather than as a cleaning mop. Use of the second container 18 is not essential in such cases, since only a very small amount of dirt will ordinarily be picked up during the mopping operation. Accordingly, this container may be detached from the main container 12 and the latter container filled to an appropriate level with clean water which is used in wetting the mopping element 23 to enhance the dust pick-up effectiveness thereof. In this type of use as in the floor scrubbing use explained above, the plate 20 is used in conjunction with the squeezing screen 17 of the pail structure 10 to squeeze the mopping element dry at desired intervals. Here, however, the water contained within the element 23 is expunged directly into the cleaning fluid, but without causing intolerable contamination of the fluid for the reason just pointed out.

From the foregoing explanation, it will be understood that the present improved mopping apparatus represents a distinct advance in the art in that it serves completely to obviate two of the foremost disadvantages of conventional mopping equipment. Thus it affords a completely acceptable solution to the problem of avoiding frequent and undesired contamination of the cleaning solution with the dirty liquid picked up by the mopping element as the mopping operation proceeds. Secondly, it completely eliminates the necessity for the mop user to stoop over, either for the purpose of carrying out the mopping operation or for the purpose of squeezing out the mopping element when this element becomes soaked with dirty liquid. Moreover, the structure is simple in the extreme and all components thereof are capable of being manufactured and assembled through the use of low cost, high speed production methods. Further, the apparatus is of very rugged construction such that, with the exception of the mopping element per se, it will withstand hard usage for an extended period of time. As regards the mopping element per se, which is the only replaceable element of the apparatus, the described novel arrangement for detachably connecting this element to the plate 20 permits of

easy and rapid replacement of this element as required.

While one embodiment of the invention has been described, it will be understood that various modifications may be made therein which are within the true spirit and scope of the invention as defined in the appended claims.

I claim:

1. A mop pail structure comprising an open-top liquid container of substantially rectangular shape, a U-shaped carrying bail shaped and sized to match approximately either one-half of the upper edge contour of said container, means pivotally mounting said bail on said container for pivotal movement relative to the open top of said container between a raised carrying position and a pair of diametrically opposed lower positions overlying one or the other half of the open top container, and mop squeezing means mounted upon and extending between the legs of said bail to cover a portion of the open top of said container when said bail is in one of its lower positions wherein said mop squeezing means is in a mop squeezing position, said mop squeezing means having openings therethrough through which liquid squeezed from a mop may drain into said container.

2. A mop pail structure comprising an open-top liquid container of substantially rectangular shape, a U-shaped carrying bail shaped and sized to match approximately one-half the upper edge contour of said container, means pivotally mounting said bail on said container for pivotal movement relative to the open top of said container, between a raised carrying position and a pair of lower positions overlying one or the other of the upper open halves of the container, means defining an open-top liquid receiving well within said chamber adjacent one end wall thereof, and mop squeezing means mounted upon and extending between the legs of said bail to at least partially cover the open top of said well when said bail is in one of its lower and effective mop squeezing positions, said mop squeezing means having openings therethrough through which liquid squeezed from a mop may drain into said well.

3. A mop pail structure comprising an open-top liquid container of substantially rectangular shape, a U-shaped carrying bail shaped and sized to match approximately one-half the upper edge contour of said container, means pivotally mounting said bail on said container for pivotal movement relative to the open top of said container between a raised carrying position and a pair of lower positions overlying one or the other half of the open-top container, a second open-top container disposed within said first-named container adjacent one end wall of said first-named container to define a liquid receiving well, said second container having a side wall slanting toward said one end wall of said first-named container, means for detachably securing said second container to said first-named container, and mop squeezing means mounted upon and extending between the legs of said bail to at least partially cover the open top of said second container when said bail is in one of its lower and effective mop squeezing positions, said mop squeezing means having openings therethrough through which liquid squeezed from a mop may drain into said well.

EDWARD A. TWERDAHL.
